Inventor:

Leyman W. Merriman,

By his attorney, Charles S. Godding.

UNITED STATES PATENT OFFICE.

LYMAN W. MERRIAM, OF FITCHBURG, MASSACHUSETTS.

MACHINE FOR MOISTENING AND SEVERING STRIPS OF GUMMED PAPER.

No. 820,512.

Specification of Letters Patent.

Patented May 15, 1906.

Application filed December 18, 1905. Serial No. 292,284.

To all whom it may concern:

Be it known that I, LYMAN W. MERRIAM, a citizen of the United States, residing at Fitchburg, in the county of Worcester and State of Massachusetts, have invented new and useful Improvements in Machines for Moistening and Severing Strips of Gummmed Paper, of which the following is a specification.

This invention relates to that class of machines in which there is a moistening device, a severing device, and a strip of paper in the form of a roll, said strip of paper provided on one side with adhesive material, said machine so constructed and arranged that the free end 15 of said strip of paper may be drawn across said moistening device and the moistened portion may be cut off by said severing device. In machines of this class now in use the moistening device intervenes between the 20 roll of paper and the severing device, and the arrangement is such that the severing device fails to cut off all of the moistened portion. As a consequence the moistened portion left on said strip is unpleasantly sticky to handle, 25 and when the adhesive material on said moistened portion is subsequently remoistened said adhesive material becomes ineffective for the purpose intended.

The object of this invention is, first, to provide a machine for moistening and severing strips of gummmed paper so constructed and arranged that the severing device shall cut off a portion of said strip of paper at the dividing-line between the moistened and unmoistened portions, and, second, to provide a machine that shall be very simple and compact and whose center of gravity shall be low, thus making it difficult to upset. This result is obtained by placing a roll of paper in a substantially horizontal position with its axis of rotation consequently extending in a substantially vertical direction, the paper after being unwound from the roll being given a quarter-turn and subsequently moistened, while the 40 knife located between the moistening device and the roll of paper is in such a position that when the paper is cut off the line of cut will come substantially on the line dividing the moistened portion of the paper from that 45 which is not moistened.

The invention consists in a machine comprising in its construction a moistening device, a knife, and a strip of paper in the form of a roll, said strip of paper being provided on one side with adhesive material, said knife being located between said roll of paper and

said moistening device, said knife being so located with relation to the moistening device that the paper will be cut off substantially on a line dividing the portion of said paper which 50 has been moistened by the moistening device and the dry portion of said paper.

The invention further consists in a device of the character set forth of a roll of paper arranged with its axis of rotation in a substantially vertical plane, means for imparting a quarter-turn to a strip of paper after it has been unwound from said roll, a moistening device, a severing device, and means for guiding said strip.

The invention finally consists in the combination and arrangement of parts set forth in the following specification and particularly pointed out in the claims thereof.

Referring to the drawings, Figure 1 is a 75 plan view of my improved machine for moistening and severing strips of gummmed paper. Fig. 2 is a side elevation of the same viewed from the right of Fig. 1. Fig. 3 is a section on line 3 3 of Fig. 1. Fig. 4 is a section similar to Fig. 3 of a modified form of my improved machine for moistening and severing strips of gummmed paper.

In the drawings, 5 is a base having a post 6 extending vertically therefrom. A reel 7, 85 pivoted on the post 6, is adapted to carry a roll of paper 8. A casing 9, surrounding and covering the roll of paper 8, is held down against the base 5 by a thumb-nut 10, having screw-threaded engagement with the post 6. 90 The casing 9 is prevented from rotating on the post 6 by pins 11, fast to said base. The casing 9 is provided with an orifice 12, one edge 13 of said orifice forming an angle of substantially forty-five degrees with a plane 95 which intersects said orifice and in which the median axial line of the post 6 lies.

A roll 14 is journaled on a vertical pin 15, said pin fast to the base 5. A water-receptacle 16 is provided with a guide-plate 17 and a knife 18 integral therewith. The guide-plate 17 is provided with a slot 19, and the knife 18 is provided with a preferably serrated edge 20. A moistening device 21 consists of a frame 22, around which extends an 105 endless belt 23, preferably formed of textile material. The moistening device 21 is partly submerged in water contained by the water-receptacle 16, the endless belt 23 of said moistening device acting to draw said water upwardly by capillary attraction. The strip of paper 24 as it is unwound from the roll 8

passes around the roll 14 and outwardly through the orifice 12, the edge 13 of said orifice imparting a quarter-turn to said strip of paper and directing said strip upwardly, said

5 strip passing through the slot 19.

A guide-bar 25, fast to the casing 9 and preferably parallel to the edge 13 of the orifice 12, is adapted to hold a portion of the strip of paper 24, which intervenes between

10 said edge and the slot 19, in a substantially vertical plane, this resulting in the free end 26 of said strip of paper being held normally out of contact with the endless belt 23. The thumb-nut 10 may be screwed against the 15 casing 9 with more or less pressure, thus springing the top of said casing downwardly against the reel 7 and increasing friction on said reel.

The operation is as follows: The operator 20 with his thumb and finger grasps the free end 26 of the strip of paper 24 and draws it across the upper portion 27 of the endless belt 23, thus moistening the adhesive material with which the strip of paper 24 is coated.

25 Having drawn out the desired length of paper, the operator swings the free end 26 toward the right, Figs. 1 and 3. It will be seen that the nearest point of contact of the strip of paper 24 with the upper portion 27

30 of the belt 23 is equal in distance from the slot 19 to the distance of the edge 20 of the knife 18 from said slot. As a consequence the dividing-line between the moistened and unmoistened portions of the strip of paper 24 35 will be swung on the arc α as the free end 26 is swung toward the right, thereby causing said dividing-line to exactly coincide with the edge 20 of the knife 18. Then the operator imparts to the free end 26 a quick movement toward the right and downwardly, 40 portion from the strip of paper 24. The moistened portion may then be utilized for any desired purpose, such as the sticking of the wrapper of a package.

45 In the modified form of my invention (shown in Fig. 4) the moistening device 21', Figs. 1 and 3, thus severing the moistened consisting of a roll 28, pivoted at 29 to the water-receptacle 16', is substituted for the 50 moistening device 21 of the preferred form, hereinbefore described.

Having thus described my invention, what I claim, and desire by Letters Patent to secure, is—

55 1. A device of the character described, adapted to hold a roll of paper, a moistening device, means to guide a strip of paper from said roll toward said moistening device, and a cutter adapted to sever a portion of said 60 paper from said strip between said roll and said moistening device substantially on a line dividing the portion of said paper moistened by said moistening device and the dry portion of said paper.

65 2. A device of the character described,

adapted to hold a roll of paper arranged with its axis of rotation in a substantially vertical plane, means for imparting a quarter-turn to a strip of said paper after it is unwound from said roll, a receptacle adapted to contain fluid, a moistening device adapted to be partly submerged in said fluid, and means for guiding said strip.

3. A device of the character described, adapted to hold a roll of paper arranged with its axis of rotation in a substantially vertical plane, means for imparting a quarter-turn to a strip of said paper after it is unwound from said roll, a receptacle adapted to contain fluid, a moistening device adapted to be partly submerged in said fluid, and means for guiding said strip, and means for severing the free end of said strip.

4. In a device of the character described, means for holding the roll of paper with its axis of rotation in a substantially vertical plane, means for imparting a quarter-turn to a strip of said paper after it is unwound from said roll, a vertical pin around which said strip passes before reaching said means for imparting a quarter-turn, a receptacle adapted to contain fluid, a moistening device adapted to be partly submerged in said fluid, and means for guiding said strip.

5. A machine for moistening and severing strips of gummed paper, adapted to hold a roll of paper arranged with its axis of rotation in a substantially vertical plane, means for imparting a quarter-turn to a strip of said paper after it is unwound from said roll, a moistening device, a severing device, and means for guiding said strip toward said moistening device.

6. A machine for moistening and severing strips of gummed paper, adapted to hold a roll of paper arranged with its axis of rotation in a substantially vertical plane, means for imparting a quarter-turn to a strip of said paper after it is unwound from said roll, a moistening device, a severing device, and means for holding the free end of said strip normally out of contact with said moistening device.

7. A machine for moistening and severing strips of gummed paper, adapted to hold a roll of paper arranged with its axis of rotation in a substantially vertical plane, means for imparting a quarter-turn to a strip of said paper after it is unwound from said roll, a moistening device, a severing device, a paper-guide located adjacent to said moistening device, and means for holding in a substantially vertical plane a portion of said strip which intervenes between said paper-guide, and means for imparting a quarter-turn to said strip.

8. A machine for moistening and severing strips of gummed paper, adapted to hold a roll of paper arranged with its axis of rotation in a substantially vertical plane, means

- for imparting a quarter-turn to a strip of said paper after it is unwound from said roll, a receptacle for water, a moistening device adapted to be partly submerged in said water, a 5 guide through which said strip may be drawn across said moistening device, and a severing device located adjacent to said guide.
9. A machine for moistening and severing strips of gummed paper, adapted to hold a 10 roll of paper arranged with its axis of rotation in a substantially vertical plane, means for imparting a quarter-turn to a strip of said paper after it is unwound from said roll, a receptacle for water, a moistening device adapted to be partly submerged in said water, a 15 guide through which said strip may be drawn across said moistening device formed integral with said receptacle, and a knife also formed integral with said receptacle.
20. In a machine for moistening and severing strips of gummed paper, a base, a central post extending vertically therefrom, a reel pivoted on said post adapted to hold a roll of paper, a casing surrounding said roll 25 provided with an orifice one edge of which forms an angle of substantially forty-five degrees with a plane intersecting said orifice and in which the median axial line of said post lies, a receptacle for water mounted on 30 said casing, a moistening device adapted to be partly submerged in said water, a guide through which said strip may be drawn across said moistening device, and a device for severing the free end of said strip.
35. 11. In a machine for moistening and severing strips of gummed paper, a base, a central post extending vertically therefrom, a reel pivoted on said post adapted to hold a roll of paper, a casing surrounding said roll 40 provided with an orifice, means for imparting a quarter-turn to a strip of said paper after it is unwound from said roll, a receptacle for water mounted on said casing, a moistening device adapted to be partly submerged in 45 said water, a guide through which said strip may be drawn across said moistening device, and a device for severing the free end of said strip.
12. A machine for moistening and severing strips of gummed paper, adapted to hold a 50 roll of paper arranged with its axis of rotation in a substantially vertical plane, a vertical pin around which a strip of paper passes after it is unwound from said roll, means for 55 imparting a quarter-turn to said strip after it leaves said pin, a moistening device, a severing
- ing device, and means for guiding said strip toward said moistening device.
13. A machine for moistening and severing strips of gummed paper, adapted to hold a 60 roll of paper arranged with its axis of rotation in a substantially vertical plane, a vertical pin around which a strip of said paper passes after it is unwound from said roll, means for imparting a quarter-turn to said 65 strip of paper after it leaves said pin, a moistening device, a severing device, and means for holding the free end of said strip normally out of contact with said moistening device.
- 70
14. A machine for moistening and severing strips of gummed paper, adapted to hold a roll of paper arranged with its axis of rotation in a substantially vertical plane, means for adjusting the friction on said roll, means for imparting a quarter-turn to a strip of said paper after it is unwound from said roll, a moistening device, a severing device, and means for guiding said strip toward said moistening device.
- 75
15. A machine for moistening and severing strips of gummed paper, adapted to hold a roll of paper arranged with its axis of rotation in a substantially vertical plane, means for imparting a quarter-turn to a strip of said 80 paper after it is unwound from said roll, a receptacle for water, an endless belt of fabric adapted to be partly submerged in said water, a removable frame around which said belt extends, a severing device, and means for guiding said strip toward said belt.
- 85
16. A machine for moistening and severing strips of gummed paper, adapted to hold a roll of paper arranged with its axis of rotation in a substantially vertical plane, means for imparting a quarter-turn to a strip of said 90 paper after it is unwound from said roll, a water-receptacle provided with a guide-slot in one wall thereof, a knife integral with said wall, and a moistening device adapted to be 95 partly submerged in said water, the nearest point of contact of said strip of paper with said moistening device being equal in distance from said slot to the distance of the edge of said knife from said slot.
